FORD ALEXANDER, OF TAFT, CALIFORNIA.

ELECTRIC-BLASTING-CAP PROTECTOR.

1,218,504.

Specification of Letters Patent.

Patented Mar. 6, 1917.

Application filed June 29, 1916. Serial No. 106,633.

To all whom it may concern:

Be it known that I, FORD ALEXANDER, a citizen of the United States, residing at Taft, in the county of Kern and State of California, have invented new and useful Improvements in Electric-Blasting-Cap Protectors, of which the following is a specification.

This invention relates to a blast cap 10 protector and detonating controller, and particularly pertains to an electrically ignited water proof concussion cap for use in deep well blasting.

It is common practice in the course of 15 drilling deep wells whether they be of oil, gas or water, to explode nitroglycerin or other highly explosive compounds at the bottom of the well to increase the flow of the well. It has been a comparatively 20 simple matter to explode such charges in wells which are empty, but it has been difficult to operate in well shafts partly filled with liquid. This is due to the fact that weights which are ordinarily dropped down 25 a casing are robbed of their force when they strike the liquid and will not hit the explosive with enough power to set it off.

The principal object of this invention is to provide an explosive cap particularly 30 adapted for use beneath surface of a body of water and which will be impervious to moisture and readily exploded.

Another object of this invention is to provide a cap which is not liable to explode 35 prematurely due to external pressure upon the shell which would cause its collapse.

Another object is to provide a cap of the class named which will be electrically ignited in a simple and certain manner.

40 A further object is to provide a water proof detonating cap which is simple in its construction and which may be inexpensively manufactured.

Other objects will appear hereinafter.

45 The invention is illustrated in the accompanying drawings in which:

Figure 1 is a view of a well casing in vertical section with portions of its length broken away and illustrates the application

and use of the water proof detonating caps 50 with a can of nitroglycerin.

Fig. 2 is a view in elevation showing the cap in detail and particularly illustrating the manner in which its outer surface is water-proofed.

Fig. 3 is a view in vertical section as seen on the line 3-3 of Fig. 2 and shows the interior construction of the cap as well as the manner in which the explosive charge is ignited.

Referring to the drawings more particularly, 10 indicates a well casing which is driven into the ground and here shown as being partly filled with water. The lower end of the casing terminates adjacent the 65 bottom of a well shaft and it is the object of this invention to provide means which may be used with safety and surety to loosen the earth adjacent the end of the well casing so that it may be further driven. As shown 70 in the drawings, this is accomplished by placing a container 11 of high power explosive at the bottom of the casing and setting it off by the shock produced by detonating caps 12 which are preferably positioned one 75 above and the other beneath the container. The essence of the present invention resides in the construction of these caps.

The caps 12 are formed with cylindrical body portions 14 which may be made of any 80 suitable material but are preferably formed of cast iron or glass. The body portion 14 of each cap is tapered at its lower end to allow it to pass downwardly through the water with slight resistance and has an electrical conduit opening 15 formed in the lower tapered end and in communication with an explosive chamber 16. The explosive chamber 16 is adapted to receive an explosive cap 16' which is formed with a thin 90 metallic shell and is preferably filled with fulminate of mercury. The chamber 16 extends longitudinally of the body 14 and communicates with an enlarged longitudinally extending bore 17 which is provided 95 for the reception of an explosive cap 17' similar in construction to the cap 16'. The bore 17 terminates within an enlarged cham-

ber 18 which is threaded internally to receive a plug 19. The portion 18 of the bore is considerably longer than the plug and thus provides a chamber 20 for a purpose 5 which will hereafter be disclosed.

In order to water-proof the cap or body member 14, the chambers 16, 17 and 18 are treated with shellac prior to charging them with their explosive charges. After being 10 charged, the chamber 20 is filled with shellac and pressed upon the charge by the plug 19. When the device has been assembled, the outer surface of the body portion is treated with shellac and water-proof tape 21 15 wrapped thereupon. This tape is afterward covered with shellac and the device is thus made thoroughly water-proof.

As a means for igniting the charge within the cap, a pair of electrical conductors 20 22 and 23 are led through the opening 15 into the chamber 16 and through the lower end of the cap 16'. To properly seal the cap at the point where the conductor passes through and to insure the explosion of the 25 charge within the cap, the conductors are surrounded at their point of entrance with plugs of sulfur which are fusible as well as dielectric. The intervening space between the plugs is bridged by a platinum 30 wire 24 which communicates between the conductors 22 and 23 and generates sufficient heat when charged with electricity to set off the fulminate.

In the manufacture of the cap, the body 35 portion, which has been previously treated with shellac as described, is fitted with the explosive caps 16' and 17'. The cap 16' is wired as described and the wires are adapted to be led to a battery 26 which is 40 controlled by a switch 27. It may be here noted that the wall of the body portion 14 is of sufficient strength to prevent the collapse of the cap under pressure and yet is fragile enough to disintegrate when the 45 charge explodes. When the explosive caps are in place within the body, a quantity of shellac is placed over the upper cap and pressed downwardly by the plug 19, after which the device is treated with shellac and 50 wrapped with the tape 21, which is subsequently shellacked. The cap is now ready for use and may be placed within any confined position and at the exact point at 55 which an explosion is desired without danger of premature ignition. When the cap is so placed, the fulminate may be instantly exploded by passing a current of electricity through the conductors 22 and 23 and the platinum wire 24. The heat generated by 60 the current passing through the platinum wire is sufficient to explode the fulminate in the cap 16' and this will subsequently explode the larger cap 17'. The concussion of these explosions is sufficient to cause the

explosion of the nitro-glycerin adjacent 65 which the explosive member 14 is positioned.

It will thus be seen that I have provided a detonating cap which is impervious to moisture, will not readily collapse under external pressure, and which may be safely 70 handled and ignited to set off a charge of high power explosive by its concussion.

I claim:

1. A detonating cap comprising a cylindrical body member of fragile material and 75 having a pointed end, said member having a relatively small initial explosive chamber and a relatively large explosive chamber connected therewith, the walls of said chambers being coated with a water-proof layer, 80 a screw plug closing said large chamber, a water-proof layer inclosing said body member, a water-proof wrapping incasing the said member, a second water-proof layer on the exterior of said wrapping, and electrically operated means for exploding the charge in said small chamber.

2. A detonating cap comprising a cylindrical body member of fragile material having 90 a relatively small initial explosive chamber and a relatively large explosive chamber connected therewith, the walls of said chambers being coated with a water-proof composition, a plug closing said large chamber, a water-proof fabric forming a case for said member, said casing having a coating of water-proof varnish, and electrically operated means for exploding the charge in said small chamber.

3. A detonating cap comprising a one-piece cylindrical fragile shell member, said member having a tapered end and a pair of connected explosion chambers of different diameters in longitudinal alignment and axially disposed in said shell member, the smaller chamber being adjacent to the tapered end of said shell member, the larger chamber having its outer end open, whereby both chambers may be filled with explosive 100 charges, a screw plug closing said open end of said larger chamber, means for initially exploding the charge in said smaller chamber, and a water-tight covering incasing said shell member.

4. A detonating cap comprising a one-piece cylindrical fragile shell member having 105 a pair of connected explosion chambers of different diameters in longitudinal alignment axially disposed in said shell member, one of said chambers opening to the end of said shell member, a plug closing said open end of said chamber, means for initially exploding the charge in said smaller chamber, and a water-tight covering incasing said shell member.

5. A detonating cap comprising a cylindrical body member of fragile material and having a longitudinal explosive chamber

therein, the walls of said chamber being coated with a water-proof layer, a removable closure for said chamber, said member being provided with a water-proof coating 5 on its exterior, a water-proof fabric wrapped about the member and forming a casing therefor, said casing being provided with a

water-proof coating on its exterior, and electrically operated means for exploding the charge in said chamber.

In testimony whereof I have signed my name to this specification. 10

FORD ALEXANDER.
